YARN FORMING MACHINE

Application filed July 1, 1927. Serial No. 202,796.

This invention relates to yarn and to a process and machine for manufacturing the same, and particularly to a machine for forming yarn out of asbestos fibres.

5 One of the objects of the invention is to produce a yarn which has a plurality of reinforcing elements wound in spaced relation thereon.

Another object of the invention is to provide a method of forming yarn by simultaneously associating several yarn forming elements.

Another object of the invention is to provide a method for forming a fibrous material 15 around a reinforcing core and binding the fibrous material to the core.

Another object of the invention is to provide a machine for making yarn which will feed several yarn making elements through 20 a die and associate the elements so fed in a manner whereby the strength and durability of the yarn are greatly increased.

Another object of the invention is to provide a yarn making machine with means to 25 stop the machine in case of the breakage of any one of the several elements making up the yarn.

Another object of the invention is to provide a means to prevent a partly formed yarn 30 from twisting as it passes through the machine.

Other objects and objects relating particularly to economies of manufacture will be 35 apparent as the description of the invention proceeds.

Broadly, the invention comprises a machine in which is supported a spool of core material such as cotton thread or string and a supply of fibrous material preferably in 40 the form of a rolled narrow strip of paper-like asbestos material. The cotton thread is led down through a die together with the strip of paper-like asbestos material in such a manner that the strip of paper is formed 45 around the cotton thread or string and at the same time a pair of reinforcing elements such as fine wire are caused to wrap around the thread and paper strip forming a double spiral winding around the core and strip.

50 Means is also provided to thereupon twist the

strand thus formed so that the reinforcing elements are tightened about the paper core and to wind the completed yarn upon a spool which is properly mounted in the machine.

One embodiment of the invention has been 55 illustrated in the accompanying drawings in which,

Fig. 1 is a side elevation of a yarn forming machine embodying my invention;

Fig. 2 is a sectional plan view taken on the 60 line 2—2 of Fig. 1 and showing the driving mechanism;

Fig. 3 is a front view of the driving mechanism taken on the line 3—3 of Fig. 1;

Fig. 4 is a sectional front view of a detail 65 of the starting handle taken on the line 4—4 of Fig. 2;

Fig. 5 is a cross-section of the yarn elements taken at a point adjacent the entrance of the 70 elements into the machine;

Fig. 6 is a sectional plan view of the tube through which the yarn elements are drawn and is taken on the line 6—6 of Fig. 7;

Fig. 7 is an enlarged front elevation partly 75 in section of the element combining mechanism;

Fig. 8 is a sectional front elevation of the feeding and twisting mechanism;

Fig. 9 is a sectional plan view of a portion 80 of the feeding mechanism taken on the line 9—9 of Fig. 8;

Fig. 10 is an elevation partly in section of a portion of the winding device showing the manner of removing the spool therefrom;

Fig. 11 is a front elevation of the element 85 supporting part of the machine showing the stopping means controlled by the continuity of the various elements; and

Fig. 12 is a side view of the mechanism 90 shown in Fig. 11.

The invention is illustrated in connection with a frame work of conventional design which supports the same. An upright 10 comprising a portion of this frame supports a horizontal angle 11 on which is mounted 95 a bearing bracket 12 by any desired means such as the bolts 13. This bracket is bored to form a bearing 14 and has a U-shaped arm 15 extending downwardly and supporting a second bearing 16 directly below the bearing 100

14. The bearing 16 is bored to the same diameter as the bearing 14 for a portion of its length and the lower portion thereof has a bore of a smaller diameter suitable to accommodate snugly a tube 17 which extends upwardly through the bearing 14 and is adapted to receive the yarn forming elements at its upper end thereof. The tube 17 may be fixed relative to the bearing 16 by means of a screw 18 engaging a suitable groove 18' in the tube so that the same is held from rotation with respect to the frame of the machine. A sleeve 19 is adapted to fit around the tube 17 and into the larger diameter bore 15 of the bearing 16 which forms a bearing for this sleeve. A pulley 20 is mounted upon the sleeve 19 and may be rigidly secured thereto by a screw 21. The sleeve 19 extends upwardly through the bearing 14, which 20 guides the same, to a point somewhat above the upper edge of this bearing.

A U-shaped bracket 22 having a somewhat enlarged base 23, which is bored out to fit snugly over the sleeve 19, is attached to the sleeve 19 by any desired means so that when the pulley 20 is rotated, the sleeve 19, together with the bracket 22 is also rotated. The enlarged portion 23 on the bracket 22 is extended downwardly to form a hub 24 which rests upon the top of the bearing 14 and supports the weight of the bracket 22 and associated parts. A spool 25 preferably of fine brass wire or other reinforcing material is adapted to fit loosely over the tube 17 so that it may freely rotate thereabout and rests upon the enlarged portion 23 in the bracket 22 and also upon the top of the sleeve 19 which may be formed flush therewith. I preferably provide a leather washer 26 between the bottom of the spool 25 and the enlarged portion 23 of the bracket to prevent the spool 25 from turning too fast upon the tube 17. About midway up each arm of the bracket 22, and on the inner side thereof, I provide a lug 27 upon which rests a brace or support 28 for the purpose of supporting a second spool of wire or other reinforcing material 29. A leather washer 30 may also be provided to fit between the bottom of the spool 29 and the support 28 to prevent too rapid rotation of the spool. The brace or support 28 may be slotted at the ends as at 31 and a rib 32 may be provided on the inner edge of the arms of the bracket 22 just above the lug 27 so that the support or brace 28 may fit upon the lugs 27 and be held against any horizontal movement by the slots 31 engaging the ribs 32. An opening 33 is provided in the support 28 to permit the tube 17 to pass therethrough.

A grooved freely rotatable pulley 34 is mounted upon one of the arms of the bracket 22 by a pivot screw 35 in a position about mid-way of the bottom and top of the lower spool 25. In like manner, a second pulley

36 is mounted on the other arm of the bracket 22 by a pivot screw 37 in a position substantially mid-way between the top and bottom of the upper spool 29. Arms 38 are pivotally mounted by means of the screws 39 to the upper ends of the arms of the bracket 22 and extend inwardly, the ends thereof supporting grooved pulley wheels 40 at a point somewhat above the top of the spool 29. The arms 38 are prevented from rotating too far in one direction by the lugs 38' and in the other direction by lugs 39' formed integral with the arms 38 on the inner and outer sides respectively of the arms of the bracket 22.

The upper end of the tube 17 is bored out 80 to a diameter considerably larger than the size of the yarn which passes therethrough and in the extreme upper end is rigidly set a die 41 which comprises a cylindrical plug having a hole 42 drilled therethrough through which the yarn forming elements are adapted to pass, the upper edge of this hole is rounded so as to permit the elements forming the yarn to pass into the opening without scraping or tearing the same and a groove 43 may be provided in the side of the plug 41 which cooperates with an indentation 44 in the upper end of the tube 17 to prevent the plug 41 from rotating. Below the plug 41 and forming a support for the same I preferably position three circular sections 45 which are adapted to fit inside of the enlarged bore at the top of the tube 17 in such a manner that their convex sides are adjacent each other as clearly indicated in Fig. 6 100 forming a triangular shaped opening through the upper part of the tube. A washer 46 may be provided if desired to support the sections 45 the same resting upon the shoulder formed by the enlarged bore at the top of the tube 17. 105

A cylindrical roller 47 is mounted below the lower end of the tube 17 so that the surface of the roller is tangent with the axis of the tube, a suitable bracket 48 attached to the frame of the machine being provided for this purpose. Below the roller 47 is preferably provided an angle 49 forming a part of the frame work of the machine and having a hole in the horizontal leg thereof substantially in line with the axis of the tube 17. A bearing 50 aligned with the hole in the angle 49 is attached to the same by means of the bolts 51 and provides a bearing support for the upper end of a hollow stem 52. The lower end of the stem 52 is extended on each side thereof to form an arm 53 having a pair of openings 54 one in each end thereof, in which are mounted two short shafts 55. Each of the shafts 55 have a pinion 56 attached to the upper end thereof and a pulley 57 having a plurality of grooves 58 attached to the lower end thereof. On each shaft the pinion 56 bears against the upper surface of the arm 53 and the pulley 57 bears against the lower surface of the arm 53, thereby preventing 110 115 120 125 130

axial movement of the shafts 55. The pulleys 57 may be rigidly attached to the shafts 54 by means of pins 58 in a well known manner.

The stem 52 has rotatably mounted there-
5 upon a pulley 59. This pulley has a hub 60 on its lower side to which is attached a flanged disc 61, the down turned flange 62 of which is adapted to cover the pinions 56 and mounted on the arm 53 with suitable
10 clearance therebetween. A small pinion 63 is preferably formed integral with the hub 60 and extends downwardly with respect to the hub and between the pinions 56 meshing therewith.

15 Another pulley 64 is mounted upon the stem 52, this mounting being preferably attained by threading a portion of the stem 52 to form a somewhat smaller diameter than that portion adjacent the pulley 59 so that a
20 shoulder 65 is formed upon which the pulley 64 may be tightly screwed so that the pulley 64 is fixed to the stem 52 and turns therewith.

A bar 66 positioned below the pulleys 57 is rigidly attached in any desirable manner to
25 a shaft 67 which extends downwardly and forms a rotatable support for a spool 68 upon which the yarn is adapted to be wound and which rests at its lower end in a bearing 69 suitably mounted as by screws 71 upon an
30 angle 70 which forms part of the frame of the machine. The lower end of the shaft 67 is preferably turned down slightly forming a shoulder 72 which is adapted to rest upon the top of the bearing 69. Between the bar
35 66 and the arm 53 is an upright support 73 which rigidly connects the bar 66 and the arm 53 for rotation theretogether and which rotatably supports a groove pulley 74 by means of a bearing screw 75. The pulley 74
40 is positioned tangentially of the axis of the tubular member 52 so that yarn passing down through the tubular member may pass over the pulley 74 and from thence several times around the grooved pulley 57 and over the
45 guide member 76 mounted by means of a screw 77 on one end of the arm 66. An arm 78 extends downwardly from adjacent the guide member 76, with which it may be formed integral, if desired, and has a pig tail
50 loop 79 at the lower end thereof through which the yarn may be run and which forms a means to guide the yarn on the spool 68. An angle iron 80 may be provided movably mounted with respect to the frame of the ma-
55 chine and means not shown may be provided for continuously raising and lowering the angle so that the spool 68 is continuously raised and lowered as the yarn is wound thereupon.

Means are provided to operate all the moving parts of the machine from a single rotat-
60 ing source of power. To this end a dog clutch 81 is splined to a driving shaft 82 located at the rear of the machine. This clutch is caused to move into and out of engagement with a
65 corresponding clutch member 83 on the driv-

en shaft 84 by a bifurcated lever arm 85 en-
gaging a groove 86 in the dog clutch 81. The bifurcated arm 85 is rigidly mounted on a shaft 87 which extends outwardly toward the front of the machine and is suitably sup-
70 ported in bearings 88 and 89 attached to frame members 90 and 91 respectively and at its forward end by bearing 92 mounted upon the angle iron 11. An arm 93 is rigidly at-
tached to the shaft 87 by any desirable means such as the pin 94 and has a depending lug 95 at its outer end which has its lower portion 96 reduced in thickness forming a shoul-
75 der 97, adapted to receive the end of a lever
98 the purpose of which will be hereinafter described so that the arm 93 may be held against a counter clockwise rotation when the arm 98 engages the shoulder 97. An arm 99 attached to the shaft 87 adjacent the bearing 89 is urged in a counter clockwise direction by the spring 100 which is attached to some convenient part of the frame and which therefore, ordinarily urges the shaft to rotate in a counter clockwise direction which by means of the bifurcated arm 85 will disengage the clutch members 83 and 81 thereby stopping the machine. A handle 101 preferably formed integral with the arm 93 may be raised to start the machine, thereby rotating the shaft 87 in a clockwise direction where-
80 upon it is held in raised position by the arm 98 engaging the shoulder 97.

Means is provided to support a roll or spool
102 of core material such as cotton thread or string at the top of the machine above the winding device shown in Figs. 1 and 7 and to this end a spindle 103 is supported in an upright position upon an angle 104 forming part of the framework of the machine. The spool 102 is placed over the spindle 103 and the thread or string 105 therefrom may be led up through a suitable tensioning device 106 supported on a bracket 107 and thence through a guide 107' and down through a guide loop 108 attached to another angle 109 forming part of the frame and to the die member 41 in the top of the tube 17.

I have found it desirable to provide as-
110 bestos fibres in the form of a paper-like strip
rotatably supported on a disc 112 having a pin 113 at the center thereof. The disc 112 may be supported upon a suitable bracket 114 from another brace 115 forming a part of the frame of the machine and is preferably tilted at an angle to prevent the roll 111 from slipping off of the pin 113 and also to provide a means to feed the paper-like strip into the die 41 at an angle. A roller
116 is provided, rotatably mounted on a suit-
115 able bracket 117 attached to the angle 109 and a tensioning device comprising a strip 118 of resilient metal is supported on the bracket 117 and has a conformation similar to that of the roller so that the paper-like strip may
120

be inserted between the roller and the strip 118 to place the strip slightly under tension as it is pulled over the roller.

The thread or string 105 is fed into the die 41 at a slight angle while the paper-like strip 110 is also fed at an angle clearly indicated in Fig. 11. The result of both the string and strip entering the die 41 at this angle is to wrap or curl the paper-like strip 110 around the string as indicated in Fig. 5.

The string 105 properly tensioned by the tensioning plates 106 passes through the loop 108 down into the die 41 together with the paper-like strip 110 which is properly tensioned on the other roller 116. As the strip and string pass through the die 41 the strip is curled around the string loosely and immediately thereafter comes into contact with the three sections 45 as indicated in Fig. 6 so that certain loose portions of the paper-like strip are squeezed out into the corners formed by the ends of the sections 45 which effectually prevents the strand thus formed from rotating in the tube 17.

I have found it preferable to reinforce the yarn and properly bind the asbestos strip on to the string by wrapping two fine wires around the same. This is accomplished by means of the device illustrated in Fig. 7 in which two spools 25 and 29 of fine wire 119, 120, are used. The spool 25, as above described, is mounted upon the tube 17 and rests upon the hub 23 of the U-shaped frame 22. The wire 119 from this spool is passed over the grooved pulley 34 and the grooved pulley 40 on the arm 38 to the die 41 at one side of the strand passing therethrough. The wire 120 from the spool 29 which is rotatably mounted at the upper end of the tube 17 is passed over the pulley 36 and the other pulley 40 on the other arm 38 to the opposite side of the strip as it passes through the die 41. Upon rotation of the pulley 20, the sleeve 19 and U-shaped bracket 22 is caused to rotate, thus wrapping the wires 119 and 120 around the strand which is caused to move through the tube 17 by means of the feeding device illustrated in Fig. 8 and is prevented from rotating by the triangular opening formed by the sections 45 in the upper end of the tube 17. In order to place the proper tension on the wires 119 and 120, they may be wrapped if desired several times around the pulleys 34 and 40 and 36 and 40 respectively. The strand including the wrapped wires passes down through the tube 17 around the roller 47 and into the upper end of the hollow stem 52. From here it passes over the roller 74 and around the multi-groove rollers 57 over the guide member 76 through the pigtail loop 79 to the roll 63 upon which it is wound.

The pulley 64 is rotated by means to be hereinafter described which rotates the hollow stem 52 and the bar 66 attached thereto.

The pulley 74 is therefore caused to revolve about the axis of the yarn which is tangent to the circumference of the pulley and this causes the yarn adjacent the pulley 74 to be twisted. Inasmuch as the yarn passes once over the pulley 47, this twisting action is prevented above the pulley 47 and must take place between the pulleys 47 and 74.

I have found it preferable to provide at least three grooves 58 in the multi-grooved pulleys 57 around which the yarn may be led after it leaves the pulley 74. These multi-grooved pulleys 57 constitute the feeding means for the machine and the purpose of the several grooves thereon is to provide friction between the yarn and the pulleys to prevent slipping of the yarn thereupon. Inasmuch as the pulley 64 is smaller than the pulley 59 it will be evident that this pulley will travel at a faster rate of rotation than the pulley 59, and therefore the pulleys 57 will move bodily about the axis of the stem 52 at a greater speed than the pulley 59 is moving. The pinion 63 is attached to the pulley 59 and meshes with the pinions 56 which are attached to the pulleys 57 by means of the shafts 55. Both the pulleys 64 and 59 are caused to move in the same direction and therefore, rotation of the pinions 56 and the attached pulleys 57 will depend on the difference in speed between the rotation of the pulleys 64 and 59. The rotation of the pulleys 57 is comparatively slight compared with the rotation of the pulleys 64 and 59, but may be varied by changing the relative sizes of the pulleys 64 and 59. The rotation of the feed pulleys 57, however, causes a continuous pull on the yarn and draws the same through the machine and from the spools and rolls which form the supply of the various elements forming the yarn. As the bar 66 is rotated with the shaft 67 and about the axis of the stem 52, the guide arm 78 is revolved around the spool 68 with the result that yarn is wound thereupon. The spool 68 rests upon the angle 80 and is free to turn thereupon against the action of friction so that as the diameter of the spool 68 increases as the yarn is wound thereupon, the spool may turn slightly with the yarn so as to compensate for the varying difference in circumference of the spool from the time when the spool is empty to the time when it is filled. The angle 80 is caused by means not shown to continually move upwardly and downwardly thereby properly winding the yarn in regular turns upon the spool.

The means to drive the machine comprises two grooved rollers 121 and 122 both attached rigidly to the driven shaft 84 and formed integral if desired with the clutch member 83 with which the dog clutch 81 is adapted to cooperate. A continuous belt 123 is provided and this belt is caused to pass over the pulley 121 downwardly and under a suitable

guide roller 124, around the pulley 59 turning the same in a counter clockwise direction as viewed from the top of the machine, from thence around a second guide pulley 125 and 5 upwardly over another guide pulley 126, forwardly again around the pulley 20 in a clockwise direction, over a loose pulley 129, rearwardly and downwardly passing under and around the roller 122 and thence downwardly 10 and forwardly passing under a guide roller 127 and forwardly to the pulley 64, around the same in a counter clockwise direction, under another guide pulley 128 (Fig. 3) and rearwardly to the under side of the pulley 121. The loose guide pulleys 124 and 125 may be mounted upon individual brackets 124' and 125' respectively, while guide pulleys 127, 128 and 129 may be mounted on a bracket 130 suitably supported on the frame 15 of the machine as by bolts 131. The guide pulley 126 may be mounted on the arm 126' pivoted to the bracket 130 at 130' and may be provided with a tensioning device comprising a lever 132 to which is attached a cable 20 133 which passes over a pulley 134 rotatably mounted on the frame of the machine and is attached at one end to a weight 135. A pin 131' may be provided to limit the movement 25 of the lever 126'.

30 It will be noted that the pulley 20 rotating the winding device is rotated in a clockwise direction while the pulleys 64 and 59 operating the twisting mechanism are rotated in a counter clockwise direction. This has the effect of twisting the yarn in the opposite direction to that in which the wires are wound therearound which increases the twist of the wires as originally made by the 35 twisting machine.

40 Means have been provided for stopping the machine when either of the wires break or when the paper strip or string breaks or when the supply of either of these elements becomes exhausted. To this end a lever arm 45 136 is rotatably mounted by means of a screw pivot 137 upon the angle 11 at a point slightly to the right of the U-shaped frame 22, the free end being positioned adjacent the hub 24 of the bracket 22. This lever arm 136 is curved at its free end to form a cam surface 138 on the side toward the hub 24, and is extended at its right end beyond the pivot 137 to form the arm 98 already described. A 50 spring 139 is wrapped about the pivot 137 and engages the angle 11 and the arm 136 in such a manner as to urge the left end of the lever 136 forwardly and the right end forming the arm 98 rearwardly. It will thus be evident that when the handle 101 is raised, the lever 136 rotates slightly in a counter clockwise direction so that the end of the lever 98 may move under the shoulder 97 formed on the lug 95 attached to the arm 93 and hold the handle in its upper position at 55 which time the clutch members 81 and 83 are engaged and the machine therefore in operation. The U-shaped bracket 22 has on each side thereof a lever 140. These levers extend substantially across each side of the U-shaped member 22 and are curved outwardly to fit 70 around the enlarged portion 23 forming the base of the U-shaped bracket 22. These levers are pivotally attached to the bracket 22 at opposite ends thereof as by means of screws 140' and each lever has at its free end a rod 141 pivotally attached thereto and extending upwardly along the arm of the bracket 22 farthest from the pivot of the lever, the end of which rod is pivotally attached to a lug 142 extending outwardly and 75 preferably formed integral with the arm 38 mounted on that arm of the bracket. The arms 38 being pivotally attached to the ends of the bracket 22 by means of the screws 39, are caused to tilt toward the tube 17 by the tension of the wires 119 and 120 passing over the rollers and being wound on to the yarn as it passes through the tube. Thus the lugs 142 are held in their uppermost position and likewise the rods 141 are maintained at their uppermost positions. Each of the levers 140 has a depending lug 143 which during the 80 normal rotation of the bracket 22 are slightly above the lever arm 36. When, however, either one of the wires breaks, the arm 38 which forms the guide for such wire is caused to move upwardly and outwardly by centrifugal force which causes the rod 141 attached thereto to move downwardly and the lever 140 at the end of the rod 141 also to move 85 downwardly until the lug 143 comes in the horizontal plane of the lever arm 36. When the lug 143 comes into the plane of the lever 90 136 it engages the cam surface 138 thereon and causes the lever 136 to rotate slightly in a clockwise direction about the pivot 137, thereby causing the arm 98 at the right thereof to move out from under the shoulder 97 whereupon the shaft 87 rotates in a counter 95 clockwise direction urged by the spring 100 and the clutch 81 is separated from the clutch member 83 thereby stopping the machine. The levers 140 are prevented from moving 100 downwardly too far by the lugs 39' on the levers 38 which engage the sides of the bracket 22 and limit the movement of the levers 38. A lug 136a formed on the lever 136 provides a convenient means to stop the machine 105 manually.

110 The machine may also be stopped if the paper strip or string should break or the supply thereof become exhausted by means of the following device: The lever arm 136 is provided at a point rearwardly of the rotating bracket 22 with a pair of depending lugs 144 to which is pivoted an arm 145. The forward end 146 of this arm is extended to a point adjacent the hub 24 of the U-shaped bracket 22 upon which is provided a cam 115 147. When the end 146 of the arm 145 is 120

125 130

moved upwardly it cooperates with the cam 147 as the latter rotates to push the lever 145 together with the arm 136 rearwardly, but when the end 146 of the lever 145 is at its 5 lowermost or normal position, the cam 147 passes over it without touching. The lever arm 145 is extended rearwardly to form an arm 148 to which is pivotally attached a rod or wire 149 which extends upwardly and is 10 pivotally attached to a lever arm 150 mounted upon the bearing for the pulley 116. The lever 150 extends upwardly from its pivot point and engages the arm 149 at an acute angle so that slight movements of the arm 150 will not materially move the arm 149. A lever arm 151 preferably formed integral 15 with the arm 150 extends downwardly therefrom and has a loop 152 at its lower end thereof which is adapted to bear against one 20 side of the asbestos paper strip 110. A suitable weight 153 is adapted to be adjustably supported on an arm 154 also formed integral with the arm 150 so that the tension of the loop 152 against the paper strip may be varied as desired.

If the paper strip should break, the arm 151 will move upwardly urged by the weight 153 which will cause the rod 149 to move downwardly, thereby tilting the end 146 of the lever 145 upwardly and into the plane of the cam 147. Upon the next rotation of this cam the lever 145 and arm 136 are pushed rearwardly, thereby releasing the clutch in a manner already described and stopping the machine. Inasmuch as the cotton string or thread 105 forms the strengthening core of the yarn and provides sufficient strength to pull the yarn through the machine if the string 105 should break or the supply become 35 exhausted the paper 110 will not have sufficient strength to be drawn into the machine and will tear off at a point where it enters the upper end of the tube 17. With the paper 40 broken, the machine is caused to stop as described above and hence it is evident that I have provided the means to stop the machine when either the paper strip, the string or the wires are broken or the supply thereof 45 becomes exhausted.

50 In Fig. 10 is illustrated the means whereby the spool 68 may be removed from the shaft 67 when the spool has become filled with yarn. To this end the bearing member 55 51 which supports the upper end of the hollow stem 52 has the lower edge of the opening therethrough extended toward the front so that the stem 52 may be tilted therein. There is also enough clearance between the 60 pulley 64 and the bearing 51 to permit the whole winding and feeding mechanism to be raised, thereby releasing the lower end of the shaft 67 from the bearing 69. The whole winding and feeding mechanism may then 65 be tilted forwardly so that the spool 68 may

be withdrawn from the lower end of the shaft 67.

It will also be noted that the drive pulleys used to transmit the motion from the driven shaft 84 to the machine are formed with deep U-shaped grooves as illustrated in the drawings. Thus the belts do not necessarily have to run on to the pulleys in the plane of the pulleys to stay on the pulley, but the grooves are sufficient to keep the belts running thereon even when the belt approaches the pulley at a considerable angle, and I have also found it desirable to use a round belt for this purpose as is clearly illustrated in the drawings.

While I have shown and described a paper-like strip of fibrous material in connection with my yarn forming machine, any strand of fibrous material may be used such as a roving of asbestos fibres loosely supported upon a strengthening core, the only requisite being that the fibrous material have sufficient strength to permit its being fed into the top of the tube 17.

It is evident also, that while two strands of reinforcing material have been found desirable, any number may be employed and that this material may constitute thread or any other material found desirable to reinforce the yarn and is therefore, not limited to wire.

In a yarn provided with two or more strands of reinforcing material wound in spaced turns as described above, greater tensile strength is obtained, inasmuch as the pitch of the spiral formed by the winding 100 may be much greater and its ability to elongate less than if one strand were used and the turns brought closer together which would be necessary in order to properly bind the asbestos material to the core. Such a 105 yarn forms an excellent friction element and may be woven into a fabric producing a highly efficient brake band.

It will be evident from the above, that I have provided an asbestos yarn, a process for 110 making the same and a machine for carrying out the process which forms asbestos fibre material around a reinforcing core and simultaneously wraps reinforcing elements around the same and subsequently twists the 115 same to form the completed yarn.

Many modifications of the invention may be resorted to without departing from the spirit of the invention, and I do not desire therefore, to limit myself to the modification described and illustrated in the accompanying drawings, but to interpret the invention broadly within the scope of the appended claims.

Having thus described my invention, what I claim is:

1. In a yarn making machine, means to simultaneously form a strip of paper-like material around a string of core material and tightly wind a reinforcing wire therearound;

and means to hold said material against rotation while said forming and winding operations are taking place whereby said reinforcing wire may be slightly embedded in said paper-like material.

2. In a yarn making machine, means to simultaneously form a strip of paper-like material around a string of core material and tightly wind a reinforcing wire there-around; means to hold said material against rotation while said forming and winding operations are taking place whereby said reinforcing wire may be slightly embedded in said paper-like material; and means to there-
10 after twist said material to form a yarn.

3. In a yarn making machine, a tubular member having an opening at one end for receiving yarn making elements; and means to twist said yarn making elements together
20 as they pass into said opening, said tubular member having an irregular bore adjacent said opening whereby said elements are prevented from turning as they pass through said opening.

25 4. In a yarn making machine, a tubular member having an opening at one end to receive yarn making elements; means to feed said elements through said opening; means to twist said elements as they pass into said opening; and means adjacent said opening to prevent the rotation of said elements.

30 5. In a yarn making machine, a member having an opening therein adapted to form a strip of paper-like material about a string of core material when said materials are fed through said opening; means to feed said materials through said opening; means to tightly wrap a reinforcing element around said materials as they pass into said opening;
35 and means to prevent rotation of said materials as they pass through said opening.

40 6. In a yarn forming machine, a stationary tubular member; means to feed a plurality of yarn forming elements through said member;
45 means to wind a reinforcing element around said yarn forming elements as they pass into said tubular member; and means in said tubular member to prevent the rotation of said elements as they pass therethrough.

50 7. In a yarn forming machine, a tubular member through which the yarn forming elements are adapted to be drawn; a forming die in one end of said member adapted to compact a plurality of yarn forming elements together; means to twist said elements as they pass into said die; and means within said member and adjacent said forming die to prevent rotation of said materials as they pass through said member.

55 8. In a yarn making machine, a member having an opening therein adapted to form a paper-like material about a string of core material when said materials are drawn through said opening; means to feed said materials through said opening; means to

wrap a reinforcing element around said materials as they pass into said opening and means to prevent rotation of said materials as they pass through said opening, said means comprising a plurality of members interposed in said member in such a manner as to distort the cross-section of said yarn forming materials as they pass through said member.

70 9. In a yarn forming machine, a tubular member through which a plurality of yarn forming materials are adapted to be drawn, a forming die in the end of said member adapted to form said materials into a cord having a substantially circular cross-section, means in said member to deform said cord to give it a non-circular cross-section to prevent its rotating, and means to wrap a reinforcing element around said yarn forming materials as they enter the forming die.

75 10. In a yarn forming machine, a stationary tubular member, means to draw a plurality of yarn forming elements through said member, means to wind a reinforcing element around the yarn forming elements as they pass through said tubular member, and means in said tubular member to prevent the rotation of said elements as they pass therethrough, said means comprising a plurality of laterally curved plates positioned in said member with their convex surfaces adjacent each other.

80 11. A die for a yarn forming machine, comprising a plurality of parts in triangular arrangement with convex laterally curved inner surfaces.

85 12. In a yarn making machine, a tubular member having an opening at one end to receive yarn making elements; a die in the end of said tubular member adapted to form a strip of fibrous material about a core as they pass through said tubular member; means to wind a reinforcing element tightly about said strip and core so as to cut deeply into the material of said strip; and means to simultaneously prevent the rotation of said element and to force portions of said fibrous material over said reinforcing element.

90 In testimony whereof, I affix my signature.
WILLIAM NANFELDT.
